UNITED STATES PATENT OFFICE.

ALFRED HOPKINS, OF BOSTON, MASSACHUSETTS, ASSIGNOR TO INNOVATION SPECIALTY COMPANY, A COPARTNERSHIP CONSISTING OF ALFRED HOPKINS, SAMUEL SIMONS, AND JOHN G. MACINTIRE, OF BOSTON, MASSACHUSETTS.

MILK-BOTTLE STOPPER.

1,108,842.

Specification of Letters Patent. Patented Aug. 25, 1914.

Application filed May 22, 1913. Serial No. 769,261.

To all whom it may concern:

Be it known that I, ALFRED HOPKINS, a citizen of the United States, and a resident of Boston, in the county of Suffolk and State of Massachusetts, have invented certain new and useful Improvements in Milk-Bottle Stoppers, of which the following is a specification.

This invention relates to a stopper for closing the neck of a milk bottle, such neck having a flat annular seat for a cap composed of a paper disk, and an inner wall surrounding the seat and of greater diameter than the latter.

15 The invention has for its object to provide a stopper adapted to be inserted in the bottle neck in place of the paper cap, and to form an outlet through which the contents of the bottle may be poured, the stopper being normally closed to prevent the entrance of dust, insects, etc., into the bottle.

The invention consists in the improvements which I will now proceed to describe and claim.

25 Of the accompanying drawings:—Figure 1 represents a top plan view of a milk bottle stopper embodying my invention. Fig. 2 represents a section on line 2—2 of Fig. 1.

The same reference characters indicate the 30 same parts in all the figures.

In the drawings, *a* represents the neck of a milk bottle having a flat annular seat *b* for a paper cap, and an inner wall *d* surrounding the seat, said wall being usually 35 slightly tapering so that its upper edge overhangs the seat to a slight extent.

40 My improved stopper is adapted to bear on the seat *b* and to form a liquid-tight joint with the interior of the bottle neck, and also to permit the contents of the bottle to pass through it when the bottle is held in pouring position.

The stopper is composed of a cylindrical body portion 12, preferably of a thin rigid material such as aluminum or other metal, said body portion having means at its inner end 45 for engaging an elastic packing ring 13 which is adapted to bear on the interior of the bottle neck and form a liquid-tight joint, and at the same time frictionally hold the

50 stopper in place in the neck. As here shown, the body portion 12 has an outwardly projecting flange 14 which is of less diameter than of the wall *d*. The packing ring is or

55 may be a suitably formed band of elastic rubber sprung upon the flange 14 and bearing upon the side and edge of said flange, as shown by Fig. 2. The normal thickness of the packing ring is such that when the stopper is inserted in the bottle neck, the portion of the packing ring interposed between the outer edge of the flange 14 and the wall *d* is compressed and thus caused to form a liquid-tight joint, and at the same time exert a frictional hold on the wall *d* of sufficient strength to prevent the stopper from dropping from the neck when the bottle is held in a pouring position.

60 The packing carried by the flange 14 projects outwardly so that it will not only seat against the shoulder or bottom *b*, of the recess in the top of the neck of the bottle, but also bears against the annular wall *d* of said recess. The seating against the bottom or shoulder *b* accurately defines the proper position of the entire stopper device, and also provides the main barrier against escape of the liquid, excepting through the spout hereinafter described, while the seating against the wall *d* is ample to prevent accidental separation of the device from the bottle, but at the same time permitting the device to be removed for cleaning and transferring to another bottle, without the employment of any implement for effecting the removal.

65 The stopper also includes a head 15 suitably joined to or formed with the outer end portion of the body 12, a pouring aperture and a movable closure therein being provided, so that when the bottle is held in 70 pouring position, its contents will enter the stopper and pass through its pouring orifice. The outflow however will be limited because the head 15, which is, of course, immovable, extends laterally across a large portion of 75 the horizontal area of the body 12 so that said head prevents excessive outflow of the milk or cream in case the bottle is tilted too far or too suddenly. Preferably the head 15 is inclined as illustrated in Fig. 2, therefore directing a better outflow through the pouring orifice, and also enabling the stopper to be more readily washed out internally.

80 In the embodiment of my invention here shown, the body portion of the stopper is provided with a spout 16, and the head 15 terminates at the inner end of the spout.

A lid or cover 17 is connected by a hinge 18 with the head 15, said lid being adapted to be closed on the upper edge of the spout, as shown by full lines in Fig. 2, and to be raised therefrom, as indicated by dotted lines. One of the members of the hinge 18 is preferably provided with a stop 19 adapted to limit the opening movement of the lid, so that the lid cannot remain open by gravitation when the bottle is upright.

The spout 16, as shown in the drawings, is directed to one side, and is above the plane of the top of the bottle, so that no milk can flow back underneath the spout when the bottle is returned to upright position after pouring, and therefore, there can be no accumulation of milk to dry or turn sour upon the top of the bottle neck.

The described stopper is to be inserted in a bottle neck on the seat *b* after the usual paper cap has been removed. The stopper forms a closure which excludes dust and insects from the bottle, and permits the contents of the bottle to be readily poured out without the removal of the stopper. The stopper is provided with an air inlet 20 which admits air to replace liquid poured from the bottle, said inlet being preferably formed in the body portion 12 at the side opposite the spout.

As clearly shown in Fig. 2, the internal diameter of the tubular body portion 12 is substantially the same as the internal diameter of the bottle neck below the annular recess, and therefore, there is nothing to obstruct the outflow of milk when pouring, and nothing to prevent the flow of milk that has not been poured out, down through the neck of the bottle to the bottom thereof. In other words, there can be no accumulation of milk inside of the bottle neck or the stopper, to dry and turn sour, excepting such as may adhere to the smooth internal surfaces.

I claim:—

1. A bottle stopper consisting of two metallic members, a hinge and a packing, one of

said members comprising a cylindrical body having at one end an integral outwardly projecting flange and having at the other end a laterally extending inclined head to 50 restrict the outflow, a portion of the body being extended at one side to form a spout, the other member comprising a lid for the spout, said lid having a hinged connection with the head, the packing being carried by 55 said flange.

2. A bottle stopper consisting of two metallic members, a hinge and a packing, one of said members comprising a cylindrical body having at one end an integral outwardly projecting flange and having at the other end a laterally extending head to 60 restrict the outflow, a portion of the body being extended at one side to form a spout, the other member comprising a lid for the 65 spout, said lid having a hinged connection with the head, and an elastic band fitted over the upper and lower surfaces and the outer edge of the flange of the body to provide a packing.

3. A bottle stopper consisting of two metallic members, a hinge and a packing, one of said members comprising a cylindrical body having at one end an integral outwardly projecting flange and having at the 75 other end a laterally extending head to restrict the outflow, a portion of the body being extended at one side to form a spout, the other member comprising a lid for the spout, said lid having a hinged connection with the 80 head, and an elastic band fitted over the upper and lower surfaces and the outer edge of the flange of the body to provide a packing, the body having an air inlet out of the path of liquid escaping through the pouring orifice.

In testimony whereof I have affixed my signature, in presence of two witnesses.

ALFRED HOPKINS.
